[57] ABSTRACT

A card punch has a card insertion slot communicating with a card receiving passage, and receiving members are mounted for movement into and out of the passage. An operating device controls such movement to control the depth of insertion of a card through the slot into the passage. A plurality of punch pins are mounted for reciprocation across the passage to punch holes in a card, and a striking member is movable toward the passage and formed with a number of holes each aligned with a respective punch pin. A plurality of shield members are selectively interposable, in an operative position, between an end of a respective punch pin and the associated opening in the striking member, and cam means control movement of the shield members to the operative positions. A timing device operates the cam means to move the shield members to the operative position only at respective indicated times whereby, at any selected instant, only those shield members corresponding to the indicated time are in the operative position. A push button is selectively actuatable at any selected instant to energize a solenoid to move the striking member to cause only those punch pins then having the associated shield member in the operative position to move across the passage to punch holes in a card in the passage.

CARD PUNCH

BACKGROUND OF THE INVENTION

Various devices have been employed for punching holes in a card, but all are complex in structure and difficult to handle and operate, and very few card punch devices have a compact overall size and are adapted for practical use. However, with the advance in computer technology, the importance of card punches and card readers, as auxiliary equipment of a computer, is increasing. Consequently, ease of handling and operation of a card punch is a primary requirement in order that the card punch may be practically usable.

A card punch which is complex in construction, and consequently troublesome to handle and operate, is disadvantageous particularly in cases where the card punch is used to examine operation efficiency by recording, on a card, the time required for an operation. In such a case, time intervals required for performing various steps of an operation are recorded, with the hours and minutes as a unit, and the hours and minutes are then added. Since the holes punched in the card represent time, it may take time, with known card punches, to punch holes in the card, making it impossible to record accurately the time intervals required for various steps of an operation.

SUMMARY OF THE INVENTION

This invention relates to card punches and, more particularly, to a new, improved and simplified card punch for recording rapidly and accurately, on a punched card, time indications, such as the time required to perform various steps of an operation.

In accordance with the invention, a card punch is enclosed in a housing having an openable front door and formed with a card insertion slit in its top wall and leading to a card passage. Adjacent the slit, there is an operating button controlling operation of the punch to punch an indicated time in a card inserted in the passage. The front face of the door is provided with openings through which there are displayed time indications, and also receives an operation chart. A window in the front door enables viewing of a manually settable indicator which may be aligned with any particular operation indication. This indicator is cooperative with receiving members movable into and out of the card passage, so that the depth to which the card is inserted into the passage corresponds to the position to which the indicator has been manually moved.

Time indicator punch pins are mounted for reciprocation across the card passage, and a striking member is movable toward the passage and formed with a number of holes each aligned with a respective punch pin. A plurality of shield members are selectively interposable, in an operative position, between the end of a respective punch and the associated opening in the striking member. A cam means controls movement of the shield members to the operative positions, and a timing device operates the cam means to move shield members to the operative position only at respective indicating times so that, at any selected instant, only those shield members corresponding to the indicated time are in the operative position. The timing means is operated by a synchronous motor which is energized responsive to closing of the front door after the punch has had electric potential applied to its operating circuitry.

At the end of the time to be measured, such as the time required to perform one step of a machining operation, for example, a card is inserted into the card passage and the push button is depressed to effect energization of a solenoid which moves the striking member toward the passage to punch holes in the card corresponding to the indicated time at which the push button is depressed.

An object of the invention is to provide a card punch 10 operable to punch, in a card, small holes indicating time and in predetermined positions so that the time required for a particular machining operation or the like can be recorded on the card.

Another object of the invention is to provide such a 15 card punch in which the depth of insertion of a card into a card receiving passage can be adjusted in accordance with the type of machining operation or the like to be timed, and including an operation indicating means so that the types of operation can be recognized externally of the card punch.

A further object of the invention is to provide a card punch including a novel hole punching mechanism operatively connected to time indicating dials.

A further object of the invention is to provide such a 25 card punch which is simple in construction, substantially free of undue maintenance, and easy to handle and operate.

For an understanding of the principles of the invention, reference is made to the following description of a 30 typical embodiment thereof as illustrated in the accompanying drawing.

BRIEF DESCRIPTION OF THE DRAWING

In the Drawing:

FIG. 1 is a perspective view of a card punch embodying the invention;

FIGS. 2, 3 and 4 are, respectively, front elevation, right side elevation and top plan views of the card punch shown in FIG. 1;

FIG. 5 is a plan view of a card before holes are punched thereinto;

FIG. 6 is a plan view of the card shown in FIG. 5 after punching;

FIG. 7 is a perspective view of the casing or housing and its associated front door, with the interior components of the casing being removed and the front door or cover being open;

FIG. 8 is an exploded perspective view of a locking mechanism for the front door or cover;

FIG. 9 is a front elevation view of the internal structure of the card punch showing only the front portion of the structure;

FIG. 10 is a front elevation view of the internal structure of the card punch showing only the rear portion of the internal structure;

FIG. 11 is an exploded perspective view of various movable elements of the internal structure mounted between left and right base plates, with the right base plate being removed;

FIG. 12 is a right side elevation view of the internal structure showing the arrangement of various parts of the outer surface of the right base plate;

FIG. 13 is an exploded perspective view of mechanism for actuating an indication member and card receiving member;

FIG. 14 is a part elevation view, partly in section, of an operating knob for actuating the indication member;

FIGS. 15A and 15B are elevation views illustrating two different positions of a mechanism for arresting rotation of the knob shown in FIGS. 13 and 14;

FIGS. 16, 17 and 18 are, respectively, a front elevation view, a side elevation view and an exploded perspective view of a clutch mechanism and associated cam means;

FIG. 19 is a side elevation view, looking from the left, of the internal structure of the card punch and showing the arrangement of various movable parts on the outer surface of the left base plate;

FIG. 20 is an exploded perspective view of a mechanism for actuating "hours" opening shield members, mounted on the outer surface of the left base plate;

FIG. 21 is a perspective view of a switch-closing time holding member of a mechanism for actuating "minutes" opening shield members;

FIG. 22 is a view similar to FIG. 21 of a switch closing time holding member of a mechanism for actuating "minutes-in-tens" opening shield members;

FIGS. 23a-23d are elevation views showing the phases of ratchet wheels of mechanisms for indicating the time of day, the hours, the minutes-in-tens, and the minutes in units;

FIGS. 24a - 24d are elevation views showing the phases of cam discs for actuating the opening shield members for the time of day, the hours, the minutes-in-tens, and the minutes in units;

FIGS. 25, 26 and 27 are elevation views showing the operation of the ratchet wheel mechanism for the minutes in units;

FIG. 28 is a vertical sectional view taken along the line X-X of FIG. 9;

FIG. 29 is a vertical sectional view taken along the line Y-Y of FIG. 9 and showing the card punch as operated to punch holes in a card;

FIG. 30 is an enlarged perspective view illustrating some of the punch pins; and

FIG. 31 is a schematic wiring diagram of the electric circuitry for the illustrated embodiment of the card punch.

DESCRIPTION OF THE PREFERRED EMBODIMENT

The invention will be explained with reference to an embodiment in which the card punch is used for recording, on a card by punching holes therein, the time interval required for performing a machining operation with a lathe, milling machine, gear cutting machine, drilling machine, grinding machine, or the like.

Referring to FIG. 1, a vertically elongated casing 1 comprises a body 1a and a front cover 1b which is hinged to body 1a by hinges 2, 2 as illustrated more particularly in FIG. 7, so that cover 1b swings open forwardly and to the left. An insertion slit 1c, for a card 3 shown in FIGS. 5 and 6, is formed near the forward edge of the upper wall of body 1a and extends parallel to the front edge of the body. The position in which a card 3 inserted through slit 1c is arrested is controlled by receiving members described more fully hereinafter, and which are adapted to be operated by an operation knob 4 on the lower portion of the right side wall of body 1a. By rotating knob 4, a pointer 5, which is exposed to view in a vertically elongated window 8b of an

indication frame 1d on the front surface of cover 1b can be moved up and down.

Referring to FIG. 3, indication frame 1d is secured to the front surface of cover 1b, and the cover portion underlying frame 1d is cut-out and a transparent plate 6 is fitted into the cut-out. Plate 6 is secured to the inner surface of cover 1b by rectangular retaining members 7, 7, shown in FIGS. 3 and 7. As shown in FIG. 7, a style strip 8 is positioned on the rear surface of transparent plate 6, and is held in position by projections 8a on its upper and lower edges rotatably engaged in supports 9 on the inner surface of cover 1b adjacent its edge flanges. Strip 8 normally is biased against transparent plate 6 by springs 10 on projections 8a.

Vertically elongated windows 8b and 8c are formed adjacent the right and left edges of strip 8. Window 8b makes it possible to see, from the exterior, the pointer 5 which extends horizontally and is moved vertically by the internal structure described hereinafter. A style strip 11 is fitted in window 8c, and is formed with four square openings 11a, 11b, 11c and 11d, which are spaced apart equally in a vertical direction. From the top to the bottom, these four openings indicate whether it is morning or afternoon, the hours, the minutes-in-tens, and the minutes in units, as will be noted from FIGS. 1 and 2.

As best seen in FIG. 7, style strip 8 has an upper marginal portion 8d which is bent rearwardly and a lower marginal portion 8e which is bent forwardly. A work sheet 12, on which there are entered the items of the operations to be timed, is inserted in a space between transparent plate 6 and style strip 8. Ten items of operations, such as "Work Begun," "Work Finished," "Lathe," "Milling Machine," "Gear Cutting Machine," "Drilling Machine," "Grinding Machine 1," "Grinding Machine 2," "Finishing" and "Inspection" are entered on work sheet 12 in the indicated order from top to bottom. Pointer 5 is adapted to be moved by knob 4 between these various positions to set, correspondingly, the depth of insertion of a card into the card punch.

The top wall of body 1a carries, forwardly of insertion slit 1c, a "punch" button 13 which fits loosely, from the inside, through an opening 1e. Button 13 is supported on a free end portion 14a of a leaf spring 14 having its fixed portion secured to the inner surface of the top wall of body 1a, so that button 13 is normally biased upwardly by spring 14 to project upwardly from opening 1e.

A microswitch Sw is positioned below button 13. If button 13 is depressed, when a card is to be punched, switch Sw is actuated to effect actuation of the internal structure, described hereinafter, so that the holes representing the time can be instantaneously punched in a card.

In addition to the components already described, an L-shaped member 15 and a stepped member 16 are secured to the upper and lower portions, respectively, of the inner surface of cover 1b. Member 15 has a short leg secured to the flange at the free edge of cover 1b, and a long leg 15a which is arranged to have its end close a main switch Swo, shown in FIGS. 9, 12 and 31 and included in the internal structure, when cover 1b is closed. The base of member 16 is secured to the inner surface of a bottom flange of cover 1b substantially

vertically below member 15, and a free end portion 16a is arranged to project into body 1a when front cover 1b is closed so as to push and operate a bell crank, included in the internal structure described hereinafter and illustrated in FIGS. 9 and 12.

A locking mechanism is provided on the inner surface of the free edge flange of cover 1b to maintain cover 1b locked when it is closed. This mechanism includes locking members 18a and 18b formed with respective square openings 17a and 17b, and disposed, respectively, adjacent the upper and lower portions of the free edge of cover 1b. The members 18a and 18b cooperate with respective key-shaped members 19a and 19b which are on the inner surface of that side wall of body 1a carrying the knob 4.

As best seen in FIG. 8, members 19a and 19b are removably mounted on fixed members 21a and 21b, having an inverted triangular shape, by headed and threaded rivets 20a and 20b respectively. Each key-shaped member 19a or 19b has one arm 19a1 or 19b1 shaped like a key at its end. Members 19a and 19b are connected to each other by a connecting rod 22 extending between their other ends 19a2 and 19b2. Spiral springs 23a and 23b are mounted on the respective rivet stems 20a and 20b, and each spring has one end connected to one arm of the member 19a1 or 19b1 and the other end connected to the member 21a or 21b, respectively, so that members 19a and 19b are biased to rotate counterclockwise as viewed in FIG. 8. However, such rotation is prevented by a shaft 24 secured to the other arm 19b2 of the lower member 19b, as shaft 24 abuts against an inclined side edge of fixed member 21b.

Shaft 24 has an outer end extending through an arched opening 1f formed in the right side wall of body 1a, and a knob 25 is secured to the outer end of shaft 24. Fixed members 21a and 21b are secured by rivets to mounting fixtures 26a and 26b welded to the inner surface of the right side wall of body 1a.

If cover 1b is closed, heads 19a1 and 19b1 of members 19a and 19b will engage in the openings 17a and 17b in the respective locking members 18a and 18b, so that cover 1b can be locked and is prevented from inadvertent opening. When it is desired to open cover 1b, knob 25 is turned in the direction of the arrow of FIG. 8, and this causes members 19a and 19b to move clockwise against the bias of the respective springs 23a and 23b, so that the respective heads 19a1 and 19b1 are released from engagement in opening 17a and 17b, respectively, and cover 1b is unlocked so that it may be freely moved to the open position.

Casing 1 is formed of a thin sheet material and, in order that body 1a and cover 1b may interfit snugly, a number of auxiliary strips 1g are welded to the inner surfaces of the marginal portions of the walls of body 1a in such a manner that strips 1g project partly beyond the edges of the walls. The bottom wall of body 1a is formed with an opening 1h for wires for connecting the internal structure to a source of potential. In addition, support legs 27 are secured to the under surface of the bottom wall of body 1a, as shown in FIGS. 2 and 3, by threaded rivet shafts extending through the bottom wall and secured to the left and right base plates of the internal structure housed in body 1a.

This internal structure comprises various movable elements mounted on left and right base plates 28 and 29, as shown in FIGS. 9 and 10. These base plates have lower marginal portions 28a and 29a bent outwardly, and the threaded rivet shafts, securing support legs 27 to the under surface of body 1a, extend through the bottom wall of the body 1a and are secured to these lower marginal portions. Plates 28 and 29 extend in upright parallel relation to each other and are interconnected by a wall 30 constituting one side wall of a receiving passage for a card 3 inserted through slit 1c.

Wall 30, which is shown in FIG. 11, has marginal portions 30a and 30b bent rearwardly at right angles and welded to the inner surfaces of the forward portions of left base plate 28 and right base plate 29, respectively, as shown in FIGS. 28 and 29, so that base plates 28 and 29 and wall 30 are substantially integral with each other.

As seen in FIG. 11, a rectangular wall plate 31 is mounted on the upper front surface of wall 30 to extend parallel thereto, and has marginal portions 31a and 31b bent forwardly at right angles and welded to the inner surfaces of the respective base plates 28 and 29. Plate 31 has an upper marginal portion 31c which is inclined forwardly, and wall 30 has an upper marginal portion 30c which is inclined rearwardly, so that these two inclined portions form an inlet for card 3. This inlet is disposed immediately below insertion slit 1c.

0 A punch pin support member 32, disposed in front of the lower portion of wall plate 31, is riveted to base plates 28 and 29. Support member 32 has an inverted L-shape in cross-section, as shown in FIGS. 28 and 29, and is formed with a channel 33 in which there are ar-

5 ranged a plurality of punch pins disposed in three rows and spaced laterally apart at equal distances from each other. As best seen in FIG. 11, support member 32 includes an upper relatively thick plate 32a, a front wall

0 includes an upper relatively thick plate 32a, a front wall 32b and a rear wall 32c, the front and rear walls depending from the upper plate or wall 32a. Member 32 also has a ledge 32d integral with upper wall 32a and extending forwardly therefrom, with rear wall 32c being slightly shorter than front wall 32b. A plurality of 5 punch pins are slidably supported by front and rear walls 32b and 32c, for reciprocation, and are arranged in three rows which extend transversely, as viewed

from the front, with eleven punch pins in the upper row, six punch pins in the intermediate row and nine punch pins in the lower row. The eleven punch pins O_1 to O_{11} in the upper row are adapted to punch holes representing the hours from 1 o'clock to 11 o'clock, respectively, from right to left. The five pins S_1 to S_5 in the center or intermediate row are adapted to punch

the center of intermediate row are adapted to punch holes representing the minutes-in-tens from 10 minutes to 50 minutes, respectively, from right to left. The nine pins M_1 to M_9 in the lower row are adapted to punch holes representing the minutes from 1 minute to 9 minutes, respectively, from right to left. The pin P which is positioned to the right in the intermediate row separately from the other pins is adapted to punch a hole representing the morning (AM) or afternoon (PM). Each of the punch pins or punches has a forward portion and a rearward portion, with the forward portion being smaller in diameter than the rearward portion. The forward portions of the pins are inserted in openings formed in rear wall $32c$ of member 32, and

the rearward portions extend through openings formed in forward wall 32b so that these rearward portions project forwardly of wall 32b.

A helical expansion spring is mounted on each pin, and engaged between a metal flange, fitted over the central portion of each pin (FIG. 30), and the inner surface of wall 32c, so that the pins normally are biased to move rearwardly. Guide cutouts 32e and 32f are formed in ledge 32d and front wall 32b, for opening shield members described hereinafter. A striking member 34 is disposed in front of support member 32 and has shafts 35a and 35b secured thereto and extending perpendicularly therefrom. These shafts have forward end portions which are loosely received in guide openings 32g (FIGS. 28 and 29) formed in upper plate 32a of member 32. Striking member 34 is formed with pin receiving openings O₂₁ to O₃₁, S₁₁ to S₁₅, M₁₁ to M₁₉, and Po, corresponding to the rear ends of the respective punch pins O₁ to O₁₁, S₁ to S₅, M₁ to M₉, and P.

The opposite lateral edges of member 34 are formed with respective grooves 34a and 34b to receive respective pins 39 and 40 each secured to a respective arm 37a and 38a of a pivotal member 37 or 38, these pivotal members being pivoted on a shaft 36 with pins 39 and 40 facing toward each other, as best seen in FIGS. 12 and 19. Shaft 36 extends transversely through the upper front corners of base plates 28 and 29, and carries members 37 and 38 at its opposite end portions extending outwardly through these base plates. Arms 37a and 38a are interconnected by a horizontal arm 41 so as to act as a unit.

Each member 37 and 38 has a second arm 37b or 38b extending rearwardly along the upper end edge of the adjacent base plate 28 or 29. Each of these arms is bent inwardly to extend across a respective cut-out 28b or 29b of a base plate 28 or 29, respectively, so that its free end 37c or 38c is connected by a shaft or pin to the actuating member MGa of a solenoid MG mounted on the rear surface of the upper portion of wall 30. Upon actuation of solenoid MG, actuating member MGa is moved from the position shown in FIG. 28 to the position shown in FIG. 29. Such upward movement of member MGa causes members 37 and 38 to pivot counterclockwise about shaft 36 so as to move striking member 34 rearwardly with rods 35a and 35b sliding through guide openings 32g. The larger ends of the punch pins move into the associated openings in member 34. Portions 28c and 29c of the upper front side edges of base plates 28 and 29, respectively, are cut out as they might otherwise interfere with the sliding movement of member 34.

Wall 30 has a portion 30d adjacent and spaced from the rear surface of wall 32c of member 32, and portion 30d is offset slightly rearwardly to form a recess. This wall portion 30d is formed with small openings corresponding to the smaller portions of the punch pins, and a resilient sheet 42, of rubber or similar material, is attached to wall portion 30d and formed with transversely directed linear cuts at portions corresponding to the plurality of punch pins, as shown in FIG. 30. The provision of the cut outs is effective to remove, from a card, portions thereof severed from the card as holes are punched in the card when the card is inserted in a passage defined by the front surface of sheet 42 and the rear surface of wall 32c as some of the punch pins pro-

ject through the card. At the same time, the resilient restoring force of the cut-outs or slits of sheet 42 is effective to brush-off the severed portions of the card from the forward ends of the pins as the pins are retracted to their original positions after punching holes in the card and extending through these slits.

Referring to FIGS. 9, 11, 28 and 29, shafts 43, 44, 45 and 46 are rotatably supported by base plates 28 and 29 below the rear portions of the punch pins. The left ends of these shafts extend outwardly through base plate 28 and support drive mechanisms for the respective shafts, as will be described. Shafts 43 - 46 are adapted to rotate only counter-clockwise, as indicated by the arrows in FIG. 11. Opening shielding members have their bases loosely mounted on shafts 43 - 46 between base plates 28 and 29.

More specifically, an opening shielding member 47 has a laterally bent tab 47a adapted to move in and out of a space between the rear end of a punch pin P and the associated receiving opening Po in member 34. The base or lower end of shield member 47 is formed with a slot 47b, as best seen in FIGS. 24a and 28, which fits loosely over shaft 43 near the right end of the latter. A cam plate 48 is secured to shaft 43 adjacent the lower end of member 47 and, as shown in FIG. 24a, the cam disc or plate 48 is formed with three protrusions 48a on its outer periphery. A laterally bent tab 47c of member 47 is arranged to engage the operating periphery of cam disc 48. Thus, when shaft 43 makes one complete revolution, shield member 47 will move up and down three times, in a pivotal manner, and tab 47a consequently will move three times into and out of the space between the rear end of pin P and its receiving opening Po. The free end portion 47d of member 47 is engaged in one of the slots 32e in ledge 32d of support member 32.

Eleven opening shield members 49₁ - 49₁₁ have respective laterally bent tabs 49_{1a} - 49_{11a} adapted to be moved into and out of the space between the rear ends of the respective punch pins O₁ to O₁₁ and the associated pin receiving openings O₂₁ to O₃₁ in member 34. These eleven shield members represent the hours from 1 to 11, and have their lower ends formed with respective slots 49_{1b} - 49_{11b} loosely fitted over shaft 44 as shown in FIG. 9. Respective cam discs 50₁ - 50₁₁ are secured to shaft 44, each adjacent a respective shield member, and the shield members have laterally bent tabs 49_{1c} - 49_{11c} arranged to engage the operating peripheries of the associated cam discs.

FIG. 11 shows one cam disc 50, which is typical of all the cam discs 50. Each disc 50 is formed with a cut-out 50a, and the cut-outs or peripheral recesses 50_{a1} through 50_{a11} of the respective discs 50₁ through 50₁₁ are successively angularly displaced from each other as shown in FIG. 24b. Thus, shield members 49₁ through 49₁₁ reciprocate up and down in succession during one complete revolution of shaft 44, so that tabs 49_{1a} through 49_{11a} move successively into and out of the spaces between the rear ends of the associated punch pins O₁ - O₁₁ and the respective receiving openings O₂₁ to O₃₁. Members 49₁ - 49₁₁ have free ends 49_{1d} - 49_{11d} engaged in the guide slots 32e formed in roof 32d of support member 32.

Five opening shield members 51₁ - 51₅ include respective laterally bent tabs 51_{1a} to 51_{5a} adapted to

move into and out of the space between the rear ends of punch pins S_1 to S_5 , for punching holes representing the minutes-in-tens from 10 to 50, and the associated receiving openings S_{11} - S_{15} in striking member 34. Shield members 51₁ to 51₅ have their lower ends formed with respective slots 51_{1b} to 51_{5b} loosely fitted over shaft 45, and respective cam discs 52₁ to 52₅ are secured to shaft 45 adjacent each shield member. Shield members 51₁ through 51₅ have laterally bent tabs 51_{1c} through 51_{5c} arranged to engage the operating peripheries of the respective cam discs.

FIG. 11 illustrates one combination of a cam disc 52 and the associated shield member 51. Thus, cam disc 52₂ is formed with two diametrically opposite cut-outs or recesses 52_{2a} and 52_{2b}, and the associated pairs of cut-outs in cam discs 52₁ through 52₅ are successively angularly displaced from each other as shown in FIG. 24c. Thereby, shield members 51₁ - 51₅ reciprocate successively during one complete revolution of shaft 45, so that tabs 51_{1a} - 51_{5a} are moved successively twice into and out of the space between the rear ends of the punch pins S_1 - S_5 and the associated openings S_{11} - S_{15} . The free ends 51_{1d} - 51_{5d} extend into guide slots 32f in the lower portion of the front wall 32b of support member 32.

Nine shield members 53₁ - 53₉ have respective laterally bent tabs 53_{1a} - 53_{9a} adapted to be moved into and out of the spaces between the rear ends of respective punch pins M₁ - M₉, for punching holes representing the minutes from 1 minute to 9 minutes, and the associated receiving openings M₁₁ - M₁₉ formed in striking member 34. The bases of these shield members are formed with respective slots 53_{1b} - 53_{9b} loosely fitted over shaft 46, and respective cam discs 54₁ - 54₉ are secured to shaft 46 each adjacent an associated shield member. Each shield member includes a respective laterally bent tab 53_{1c} - 53_{9c} arranged to engage the operating periphery of the adjacent cam discs 54₁ - 54₉.

Only one combination of a cam disc 54 and the associated shield member 53 is shown in FIG. 11. The cam discs have respective cut-outs or peripheral recesses 54_{1a} - 54_{9a} which are displaced angularly from each other, in succession, as shown in FIG. 24d. Accordingly, during one rotation of shaft 46, shield members 53₁ - 53₉ are reciprocated successively so that the associated lateral tabs 53_{1a} - 53_{9a} move successively into and out of the respective spaces between the ends of punch pins M₁ - M₉ and the associated receiving openings M₁₁ - M₁₉. Free ends 53_{1d} - 53_{9d} of the shield members are engaged in guide slots 32f in the lower portion of front wall 32b of support member 32.

Respective tension springs are connected between each shield member and either one of two shafts or rods 55 and 56 extending between base plates 28 and 29 as best seen in FIGS. 28 and 29. Thus, each shield member is spring-biased to move counterclockwise, as viewed in FIGS. 28 and 29, about its associated shaft and, at the same time, to move downwardly toward its associated shaft. The counterclockwise pivoting of each shield member is limited by its free end abutting against the inner surface of striking member 34, and downward movement of each shield member is limited by engagement of its lower laterally bent tab with the associated cam disc. If shafts 43 to 46 are rotated by a timing device, described hereinafter, and the lower

lateral tabs of the shield members engage the recesses in the associated cam discs, the shield members are biased downwardly by the associated springs. During downward movement of each shield member, the associated upper lateral tab is interposed between the respective punch pins and the corresponding pin receiving opening in striking member 34.

Shafts 43 through 46 are driven in a manner such that shaft 46 makes one complete rotation in 10 minutes, shaft 45 makes one-half a rotation in 60 minutes, or a complete rotation in 2 hours, shaft 44 makes one complete rotation in 12 hours and shaft 43 makes one-sixth of a rotation in 12 hours or one-third of a rotation in 24 hours. The nine cam discs 54₁ through 54₉, secured to shaft 46 are so arranged that a recess corresponding in dimension to one-tenth of the outer circumference of the associated disc is formed in each disc, and the recesses are successively angularly displaced from each other as shown in FIG. 24d. Correspondingly, cam discs 52₁ - 52₅, secured to shaft 45, have two peripheral recesses each corresponding, in dimension, to one-twelfth the periphery of the disc, the two recesses being diametrically opposite each other and the 10 recesses being successively angularly displaced from each other so that the recesses in any two discs do not overlap. The 11 cam discs 50₁ - 50₁₁ secured to shaft 44 are so constructed that a peripheral recess corresponding, in dimension, to one-twelfth the outer periphery of the disc is formed in each disc, and the discs are so arranged that the 11 recesses are successively angularly displaced from each other so as not to overlap. Cam disc 48 secured to shaft 43 is so constructed that the three protrusions 48a of its outer periphery are arranged at equal angular distances from each other as shown in FIG. 24a.

As shown in FIGS. 10, 28 and 29, nine card receiving members 57₁ through 57₉ are arranged in vertically spaced relation along the front surface of wall 30 between this wall and the shield members. FIG. 11 shows the third card receiving member 57₃ and the sixth card receiving member 57₆. As illustrated, the card receiving members are shaped so that each comprises a transversely elongated plate having opposite end portions, such as 57_{3a} and 57_{3b}, bent laterally and apertured to receive a support shaft, such as 58₃, mounted in base plates 28 and 29.

As shown in FIG. 11, the left end of shaft 58₃ extends through a small opening formed in a vertically elongated L-shaped card guide member 59 welded to left base plate 28, and the right end of shaft 58₃ extends through right base plate 29, snap rings being fitted on the opposite ends of each shaft 58₃ and 58₆, as best seen in FIGS. 10 and 12. The upper edge of the plate of each card receiving member extends at a slight angle and includes a central portion, such as 57_{3c}, which is recessed. Respective fins, such as 57_{3d} and 57_{3e} are formed on the opposite ends of the upper edge to receive the lower end edge of an inserted card.

As best seen in FIG. 10, these fins are disposed adjacent vertically elongated recesses 30e and 30f formed, respectively, adjacent the left and right edges of wall 30. If a card receiving member is pivoted clockwise, as viewed in FIGS. 28 and 29, about its associated shaft, the fins, such as 57_{3d} and 57_{3e} will extend through recesses 30e and 30f and abut against the

inner edges of these recesses. Thus, an inserted card has its lower end edge engaged by the upper surfaces of the fins.

Card receiving member 57₆, shown in FIG. 11, is illustrated as it has been moved clockwise about its shaft 58₆. Each card receiving member includes an L-shaped side arm, such as 57₃, extending outwardly from its lower edge adjacent its right end, and formed with a bent portion 57_{3a}. As best seen in FIG. 12, side arms 57_{1f} through 57_{9g} of the card receiving members extend through respective square windows 29₁ through 29₉ in the forward middle portion of right base plate 29, and project outwardly from this base plate. This arrangement permits external control of the oscillation of the card receiving members and, by engaging and moving the bent arms 57_{1g} through 57_{9g} by a belt of an operation device, described hereinafter, it is possible to oscillate the card receiving members about the associated shafts.

As shown in FIG. 12, springs 59₁ through 59₉ embrace the right end portions of the respective shafts 58₁ - 58₉, and one end of each spring is connected to a respective side arm 57_{1f} - 57_{9f} and the other end to a respective window 29₁ - 29₉. These springs bias the card receiving members to move clockwise about the associated shafts, so that the card receiving members are biased, normally, to a position in which the associated fins abut recesses 30e and 30f to block passage of a card inserted through the receiving slot. Member 60 of FIG. 11 is welded to the inner surface of right base plate 29 and formed with cut-outs which receive the right bent end portions 57_{1b} and 57_{9b}, member 60 having an inclined upper edge 60a for guiding an inserted card.

As shown in FIGS. 10, 11, 28 and 29, a fixed receiving member 61 is arranged below the lowest movable receiving member, and is formed as a shelf which is L-shaped in end elevation and is secured to wall 30 by screws 62a. Member 61 has a horizontal portion including opposite ends 61a which extend into recesses 30f and 30e to abut the walls thereof. This fixed card receiving member functions in a manner such that, when the nine movable card receiving members have all been pivoted counterclockwise to draw their fins from recesses 30e and 30f, to open the card passage, member 61 defines the final punching position for the card.

Arranged below the member 61, there is a cover plate 63 which forms a cover for a reservoir for the punched out portions of card material. As best seen in FIGS. 11, 28 and 29, this reservoir includes a rear wall 64 extending along wall 30 in spaced relation thereto to define a passage for the punch-outs of the cards. Wall 64 has a lower portion bent rearwardly and downwardly and then forwardly and downwardly to provide an angular portion defining a reservoir 65 opening forwardly. The front opening of reservoir 65 is divided into an upper half and a lower half, with the upper half being covered by the lower marginal portion of wall 30 and the lower half being removably covered by cover plate 63.

This cover plate includes forwardly bent left and right edges, and a fixed shaft 66 mounted in base plates 28 and 29 extends through apertures in these bent edges to support plate 63 for pivotal movement. For-

wardly projecting arms 63a are formed at the upper portions of the side edges, and headed rivets 63b are secured on these arms, with bow springs 67 extending between rivets 63b and shaft 46. If rivets 63b are disposed outwardly of the imaginary line connecting support shaft 66 and shaft 46, cover plate 63 is biased, by springs 67, to move in a direction closing the opening of reservoir 65. On the other hand, if the rivets are disposed inwardly of this imaginary line, the bias of springs 67 urges cover plate 63 to move in a direction uncovering the opening of reservoir 65, or to the position shown in dotted lines in FIG. 28, and to remain in this position. The lower edge 63c of cover plate 63 is inclined forwardly to facilitate opening of the cover, and a resilient cushion 68 is secured to the rear surface of cover 63 immediately above edge 63c to absorb vibration of the cover plate, which might occur when the cover is closed. Cover plate 63 normally is closed, so that the small pieces of punched-out card material dropping downwardly through the passage defined by walls 30 and 64 are gathered in reservoir 65. When front cover 1b of casing 1 is opened and cover plate 63 is swung upwardly, the accumulated pieces of card material slide downwardly along the inclined wall and are discharged out of the casing.

As mentioned, walls 30 and 64, striking member 34, punch pin support member 32, the shield members, reservoir 65, and solenoid MG are provided between base plates 28 and 29. In addition, switch Sw and a synchronous electric motor SM are mounted between these base plates. As shown in FIG. 9, switch Sw is riveted to an L-shaped fixture 69 mounted on the upper edge of right base plate 29, and has an actuator pin positioned immediately below push button 13. Synchronous electric motor SM is mounted on the inner surface of the lower rear portion of right base plate 29, as shown in FIGS. 10, 28 and 29, and has a drive shaft SMa extending through and outwardly of right base plate 29.

A timing device, driven by motor SM, and an externally accessible operation device for operating the card receiving members will now be explained. Referring to FIGS. 12 and 13, the operation device is mounted on the outer surface of right base plate 29 and associated with a work sheet item indication device and a clutch mechanism for controlling transmission of the torque of motor SM. More specifically, the bent arms 57_{1g} through 57_{9g} of the card receiving members extend through the square openings 29₁ through 29₉ in right base plate 29 to project outwardly from the latter and to engage in respective rectangular openings 70₁ through 70₉ in a vertically elongated angular guide member 70 welded to base plate 29. A looped belt 71 extends vertically and is adapted to have its outer surface contact the inner surface of guide member 70 for guiding thereby. Belt 71 is trained about end portions of upper and lower shafts 72 and 73 rotatably supported by plates 28 and 29. As best seen in FIG. 11, shafts 72 and 73 are mounted between base plates 28 and 29 rearwardly of wall 30 and parallel to each other. The right ends of these shafts extend through base plate 29 and project outwardly therefrom, and the projecting shaft ends 72a and 73a mount a pulley 74 and a sprocket wheel 75, respectively. Belt 71 is trained over pulley 74 and sprocket 75 and has its opposite ends 71a and 71b interconnected by a tension spring 76.

Perforations 71c are formed adjacent one edge of belt 71 to receive the pawls or pins of sprocket wheel 75, and belt 71 is tensioned by spring 76 so as to move in opposite directions in accordance with rotation of sprocket 75. The opposite edge of belt 71 has a cut-out portion 71d whose length is substantially equal to the vertical length of guide member 70, portion 71d having an upper edge 71e and a lower edge 71f which are arranged to engage and move bent arms 57_{1a} through 57_{9a} of the card receiving members.

Belt 71 is arranged to move along the inner surface of guide member 70, so as to successively close and open openings 70₁ through 70₉. Thus, bent arms 57_{1a} - 57_{9a} are obstructed by the belt from extending into the associated rectangular openings 70₁ - 70₉. However, those openings then adjacent cut-out portion 71d of belt 71 are left open, so that the bent arms at these openings can project thereinto.

Thus, when all of the openings of guide member 70 are aligned with the cut-out portion of the belt, they are all open for the bent arms of the card receiving members to extend therethrough, so that the card receiving members pivot clockwise (FIG. 12) about the associated support shafts to close the card receiving passage. If, in this state, cut-out portion 71d of belt 71 is moved downwardly, the upper edge 71e of portion 71d first moves the uppermost bent arm 57_{1a} to cause the associated card receiving member 57₁ to pivot clockwise about support shaft 58₁ against the bias of the associated spring so as to open the initial portion of the card receiving passage. As downward motion of cut-out portion 71d is continued, the card receiving members are successively moved out of their passage-obstructing position.

If cut-out portion 71d of belt 71 is moved upwardly again after all the openings 70₁ through 70₉ have been closed by belt 71, then upper edge 71e of portion 71d successively uncovers the openings 70₁ - 70₉, starting with the lowest opening, so that the card receiving members, under the bias of the associated springs, successively pivot counterclockwise so that their bent arms project through the associated rectangular openings. Thereby, the position in which an inserted card is halted is shifted upwardly.

Sprocket 75 can be turned in either angular direction by operation of knob 4. The end 73a of lower shaft 73 mounting sprocket 57 projects outwardly beyond sprocket 75 and through the right side wall of casing 1 to extend therefrom for mounting knob 4 thereon. A rotation inhibiting mechanism is mounted between knob 4 and sprocket 75, to stop further rotation of shaft 73 after it has been rotated a predetermined amount in either angular direction by operation of knob 4.

As shown in FIGS. 12 through 15, the rotation inhibiting mechanism comprises a star member 77 having eight angular protrusions on its periphery, a cam plate 78 loosely fitted over a tubular shaft 77a secured centrally to member 77, and a click-stop lever 80. Member 77 has an integral hub 77b at its inner surface and tubular shaft 77a integral with its outer surface. Hub 77b is secured to shaft 73 adjacent sprocket 75, as illustrated in FIG. 14. Cam plate 78 comprises three segmental portions including a minor radius portion 78a, an intermediate radius portion 78b and a major radius portion 78c which are spaced from the center of cam plate 78

radial distances differing from each other. Major radius portion 78c has a radius greater than the radius of the outer end of each protrusion of member 77, and minor radius portion 78a has a radius which is less than the radius of the base of each depression in the outer periphery of member 77. The operating periphery of cam plate 78 is so arranged that minor radius portion 78a is contiguous with intermediate radius portion 78b, and major radius portion 78c is interposed between portion 78a and portion 78b. Cam plate 78 is formed with a central opening which loosely receives tubular shaft 77a, and the outer surface of member 77 carries a pin 79 which intersects the path of rotation of portion 78b and 78c of cam plate 78. Pin 79 has a forward end received in a cut-out 4b of operation knob 4.

Thus, if knob 4 is turned, shaft 73 can be rotated through pin 79, member 77 and hub 77b. Click-stop lever 80 has a free end mounting a roller 81 pressed from below against one of the recess portions in the outer periphery of member 77. Lever 80 has a channel-shape base portion 80b through the legs of which extends a shaft 82 mounted on right side plate 29. A highly resilient spring 84 embraces shaft 82 and is connected between one arm 83b, of a bell crank 83 having a channel-shaped base 83a rotatably mounted on shaft 82, and lever 80, so that lever 80 is biased counterclockwise and bell crank 83 is biased clockwise by spring 84. Counterclockwise movement of the lever 80 is limited by engagement of roller 81 with a depression in the periphery of member 77, and clockwise movement of bell crank 83 is limited by engagement of a pivoted lever 85, coupled to the other arm 83c of bell crank 83, with a heart-shaped cam for restoring a clutch mechanism to a zero position as described hereinafter. Knob 4 is prevented from disengagement axially of shaft 73 by a stop-ring 86 riveted to the end surface of shaft 73.

The described rotation limiting mechanism for shaft 73 is adapted to limit clockwise and counterclockwise rotation of the shaft through a predetermined range, as best illustrated in FIGS. 15A and 15B. More specifically, if knob 4 is turned counterclockwise, as shown in FIG. 15A, then shaft 73 is rotated counterclockwise through pin 79 and star-shaped member 77. This rotational movement is intermittent because roller 81 intermittently engages the depressions in the outer periphery of member 77. Sprocket 75 is rotated counterclockwise so that belt 71 is moved forwardly intermittently. If belt 71 moves in a manner such that all the card receiving members are moved into an upright position, in the manner described, then major radius portion 78c and intermediate radius portion 78b of cam plate 78 are retained between pin 79 and roller 81, thereby preventing further counterclockwise movement of shaft 73 so that the shaft can now be rotated only clockwise.

If knob 4 is rotated clockwise, shaft 73 is also rotated clockwise through pin 79 and member 77 so that sprocket 75 moves belt 71 upwardly. The upward movement of belt 71 is also intermittent due to roller 81 intermittently engaging the depressions in the outer periphery of member 77. As cut-out portion 71d of belt 71 moves upwardly, the card receiving members, starting with the lowest member, pivot clockwise, as viewed in FIG. 12, under the bias of the associated springs,

thereby closing the card insertion passage progressively. When all the card receiving members have been pivoted clockwise, major radius portion 78c of cam plate 78 is held between pin 79 and roller 81, as shown in FIG. 15B, thereby preventing further clockwise rotation of shaft 73. It will be noted that, although cam plate 78, loosely fitted over tubular shaft 77a, remains idle, one side edge of major radius portion 78c abuts against roller 81, and counterclockwise movement of pin 79 is inhibited when the offset portion connecting intermediate radius portion 78b of cam plate 78 to minor radius portion 78a is engaged by pin 79, so that major radius portion 78c and intermediate radius portion 78b are held between pin 79 and roller 81.

When pin 79 moves to move the connecting edge between major radius portion 78c and minor radius portion 78a of cam plate 78, only major radius portion 78c is held between pin 79 and roller 81. At this time, the other side edge of portion 78c engages roller 81, so that clockwise movement of pin 79 is thereby inhibited. Thus, shaft 73 can be rotated through only a predetermined angular distance, with the rotation being limited by the action of the stopper mechanism.

Pivotal lever 85, coupled to bell crank 83, is pivoted on a shaft 87 secured to right base plate 29, as shown in FIGS. 12 and 13, and a pin 88 on one arm 85a of lever 85 is loosely received in a forked portion 83d of the other arm 83c of bell crank 83. The other arm 85b of lever 85 extends rearwardly and carries, through a shaft at its end, a roller 89 adapted to press against the peripheral surface of a heart cam 98 from beneath, as best seen in FIG. 12. When one arm 83b of bell crank 83 is moved, as shown in FIG. 12 by the above described stepped fixture 16 secured to cover 1b of casting 1, lever 85 pivots clockwise about shaft 87, as shown by the broken line in FIG. 12, as bell crank 83 pivots about support shaft 82 counterclockwise against the bias of spring 84, thus permitting heart cam 98 to rotate.

The clutch mechanism is constructed as shown in FIGS. 16, 17 and 18, and is mounted on the lower rear portion of base plate 29, with FIGS. 16, 17 and 18 being enlarged views showing the clutch mechanism housed in an enclosure 90 riveted to base plate 29. A shaft 91 is secured to the base of enclosure 90, and has an end juxtaposed to the end of driving shaft SMa of motor SM extending through base plate 29. Loosely fitted over shaft 91, starting from its forward end toward its base, as shown in FIGS. 17 and 18, are a driving wheel 92 having ratchet teeth 92a on one surface, an engaging ring 93, formed with a peripheral cut-out 93a, an engaging ring 94 formed with a peripheral protrusion 94a arranged to engage cut-out 93a, a disc 95 having a projecting peripheral portion 95a, a disc 96 adjacent disc 95 and formed with a projecting peripheral portion 96a, and a zero position restoring heart cam 98 having its hub 97 riveted to discs 95 and 96. Engaging ring 94 is secured to disc 95, so that engaging ring 94, discs 95 and 96, and cam 98 are adapted to rotate as a unit about shaft 91.

Driving wheel 92 and engaging ring 93 are integrally connected to each other by a tubular shaft 99, and a helical expansion spring 100 is mounted between engaging rings 93 and 94 to bias wheel 92 and ring 93 axially of shaft 91. One side surface of a segmental free

end 101a of a clutch engaging and disengaging lever 101, having its base fitted over shaft 87 as shown in FIG. 13, is arranged to engage against and end surface 93b of engaging ring 93. One part of the lower side edge of lever 101 is formed integral with one part of the lower side edge of pivotal lever 85 so that, when lever 85 is pivoted clockwise about shaft 87, lever 101 is also pivoted clockwise and segmental free end portion 101a is released from engagement with end surface 93b of engaging ring 93.

Rings 93 and 94 are coupled together by engagement of protrusion 94a in cut-out 93a. As ring 93 is moved axially of shaft 91 by spring 100, teeth 92a of driving wheel 92 are brought into engagement with driving

pawls 102, 102 on driving shaft SMa of motor SM, so that the torque of motor SM is transmitted to discs 95 and 96 and to heart cam 98. However, when free end 101a of lever 101 pushes against end surface 93b of ring 93, ring 93 is shifted, against the bias of spring 100, in a direction in which it engages more firmly with ring 94, so that pawls 102, 102 disengage driving wheel 92 and thus motor SM no longer drives discs 95 and 96. One portion 101b of the upper edge of free end 101a of lever 101 is bent so that it is inclined toward base plate 29, and driving wheel 92 is shifted axially of shaft 91 a distance corresponding to the length of this bent portion.

As shown in FIG. 12, actuators Sw_{1a} and Sw_{2a} of respective microswitches Sw₁ and Sw₂, for operating a timing device described hereinafter, are disposed, as illustrated in FIG. 12, in the paths of travel of projections 95a and 96a of the respective discs 95 and 96 of the clutch mechanism. As shown in FIG. 31, switch Sw₁ is a normally closed switch and switch Sw₂ is a normally open switch. Switch Sw₁ is adapted to be opened by projection 95a of disc 95 when engaged by this projection during rotation of the disc, and switch Sw₂ is adapted to be closed when engaged by projection 96a of disc 96 during rotation of this disc. The two switches are arranged to be operated simultaneously by the respective projections 95a and 96a.

When switch Sw₁ is closed so that current is supplied to solenoids of a timing device, described hereinafter, the shield members are made operative by the timing device. If push button 13 is depressed while the shield members are being operated, the punch pins will become erratic in performance. For this reason, actuation of switch Sw₁ is effective to inhibit actuation of the electric solenoids for the striking member 34, by interrupting the supply of current therethrough to the solenoids, so that member 34 may not be operated even if the push button 13 is depressed while the shield members are being operated.

As shown in FIGS. 12 and 31, discs 95 and 96, rotated upon engagement of the clutch, are rotated clockwise about the axis of support shaft 91 by motor SM at an angular velocity of one revolution per minute. If the clutch is disengaged as lever 101 pivots about shaft 87 from the broken line position to the solid line position of FIG. 12, lever 85 also moves from the broken line position to the solid line position, together with lever 101, and roller 89 presses against the peripheral edge of heart cam 98. This causes discs 95 and 96, which are integral with cam 98, to rotate about shaft 91, thereby restoring projections 95a and 96a to

their starting positions. As mentioned, this operation is performed when cover 1b of casing 1 is opened and bell crank 83 is pivoted about shaft 82 under the bias of spring 84 to move the pin 88.

A guide bar 104 for guiding an indication member 103 having a base supported on belt 71 is disposed vertically in front of belt 71, as shown in FIGS. 12 and 13. Bar 104 is supported at opposite ends in ears 105a of an elongated support plate 105 which is at the front edge of base plate 29. Indication member 103 is formed with bent ears 103a and 103b receiving bar or rod 104, so that this bar guides member 103 in its vertical movement. Indication member 103 includes bent front and rear ends, with rear end 103c being trifurcated to grip belt 71 to connect the belt to indication member 103.

The bent front end of member 103 extends horizontally over the front surface of a style strip 106 mounted on support plate 105, and serves as a pointer 5 which is adapted to indicate each item of work sheet 12 mounted in cover 1b of casing 1. As mentioned, when cover 1b of casing 1 is closed, style strip 106 and pointer 5 permit the operator to ascertain the upward and downward movements of pointer 5 through window 8b in cover 1b. Accordingly, if knob 4 is turned to move belt 71, pointer 5 will move up and down with belt 71 so that pointer 5 indicates the item on the work sheet which corresponds to the receiving members pivoted by cut-out portion 71d. As shown in FIGS. 9 and 12, main switch Swo is mounted on base plate 29 in a position upwardly of member 103, and is arranged to be closed by the free end 15a of fixture 15 secured to the inner surface of cover 1b, when cover 1b is closed.

As mentioned, an externally accessible device for actuating the card receiving members to determine the position of an inserted card, an indication member for indicating the position of the card, and clutch mechanism for controlling transmission of power from motor SM are arranged on the outer surface of right base plate 29. In addition, a printed circuit board 107, mounting a capacitor forming part of the electric circuit, is mounted at the upper rear portion of base plate 29 as shown in FIG. 12 and, below the capacitor, there are an electrolytic capacitor and a relay RL facing the inner surface of the base plate.

Conversely, the outer surface of left base plate 28 mounts a timing device for rotating shafts 43 - 46 in accordance with elapsed time, these shafts extending between the two base plates as shown in FIG. 19. The timing device is constructed such that it rotates shafts 43 - 46 by reciprocating feed pawls actuated by solenoids and engageable with cut-out discs on the ends of the shafts extending outwardly through left base plate 28.

More specifically, a cut-out disc 108 secured to the end 43a of shaft 43 is rotated clockwise by a feed pawl 109 actuated by a solenoid Da, to rotate shaft 43 clockwise. A cut-out disc 110 secured to end 44a of shaft 44 is rotated clockwise by feed pawl 111 actuated by solenoid Db to rotate shaft 44 clockwise. Similarly, a cut-out disc 112 secured to the end 45a of shaft 45 is rotated clockwise by a feed pawl 113 operated by solenoid plunger Dc to rotate shaft 45 to the right. Finally, a cut-out disc 114 secured to end portion 46a of shaft 46 is rotated clockwise by a feed pawl 115 actuated by solenoid Dd to rotate shaft 46 clockwise.

Electric current is supplied to solenoid Da once in 12 hours through a microswitch Sw₃ (FIG. 20) adapted to be opened and closed by a free end 116a of a check member 116 preventing reverse rotation of cut-out disc 110. Electric current is supplied to solenoid Db once an hour through a microswitch Sw₄ (FIG. 19) adapted to be opened and closed by a free end 117a of a check member 117 preventing reverse rotation of cut-out disc 112. Current is supplied to solenoid Dc once every 10 minutes through a microswitch Sw₅ adapted to be opened and closed by a free end 118a of a check member 118 preventing reverse rotation of cut-out disc 114, and current is supplied to solenoid Dd once each minute through microswitch Sw₂ (FIG. 12) adapted to be opened and closed by projection 96a of disc 96 rotated on shaft 91 of the clutch mechanism.

Cut-out discs 108, 110, 112 and 114 are configured as shown in FIGS. 23a through 23d, respectively, in the indicated order. From these figures, it will be seen that disc 108 has its outer periphery formed with six cut-outs disposed equal angular distances from each other. Feed pawl 109 and a pin 119a, secured to check member 119, are adapted to press against the cut-outs of disc 108. As shown in FIG. 23b, disc 110 has twelve peripheral cut-outs spaced angularly from each other, and feed pawl 111 and a pin 116b, attached to check member 116 are cooperable with these cut-outs. Referring to FIG. 23c, disc 112 has 12 peripheral cut-outs at equal angular distances from each other, and feed pawl 113 and a pin 117b attached to check member 117, are cooperable with the cut-outs of disc 112. Disc 114 is formed with 10 peripheral cut-outs at equal angular distances from each other, and feed pawl 115 and a pin 118b, attached to check member 118, cooperate with the cut-outs of disc 114. Each of these cut-out discs, with the associated feed pawls and check members, constitutes what is known, from mechanics, as an intermittent feed mechanism. The several mechanisms are so constructed that, responsive to the actuation of the associated feed pawl, disc 108 makes one-sixth of a rotation, discs 110 and 112 make one-twelfth of a rotation, and disc 114 makes one-tenth of a rotation, to effect intermittent clockwise rotations of the respective shafts.

Feed pawls 109, 111, 113 and 115 are pivotally mounted on the free ends 120a - 123a of respective rocker arms 120 - 123 pivoted on the associated shafts 43 - 46 adjacent the respective cut-out discs 108, 110, 112 and 114. Each feed pawl is spring-biased to move clockwise to press against the operation periphery of the associated cut-out disc.

Free end 120a of rocker 120 is connected by a connecting rod 126 to a free end 125a of a pivotal lever 125 adapted to be swung by actuating bar Da₁ of solenoid Da to move clockwise about a support shaft 124. When solenoid Da is energized, an actuator bar Da₁ is pulled to the right, lever 125 pivots counterclockwise and pushes connecting rod 126 to the right, so that feed pawl 109 advances cut-out disc 108 through one-sixth of a rotation, or through 60°. A spring 128 is connected between the pivotal interconnection of lever 125 and rod 126 and a stop-pin 127. Thus, lever 125 is biased by spring 128 to swing clockwise with such swinging being limited by stop-pin 127. This arrangement is effective to assure, by regulating the length of the restoring mo-

tion of feed pawl 109, that feed pawl 109 positively engages the next cut-out after it has been advanced and then retracted to its original position by solenoid plunger Da through lever 125 and rod 126.

FIG. 20 is an exploded perspective view illustrating an hours transfer mechanism arranged to make one complete rotation in 12 hours and mounted below the just described morning and afternoon switching mechanism. Disc 110, pivotal member 121 mounting feed pawl 111, and an hour-indicating ring 136 are mounted, in the indicated order, on the end 44a of shaft 44, with disc 110 and ring 136 being fixed to shaft 44 and the rocker arm 121 being pivotal on shaft 44. Under the mentioned spring bias, the free end of feed pawl 111 is normally engaged in one of the cut-outs of disc 110.

The free end of actuating bar Db₁ of solenoid Db is connected by a pin to the base of rocker arm 121 adjacent a lower right corner thereof as viewed in FIG. 20. When solenoid Db is actuated and bar Db₁ is retracted, rocker arm 121 pivots clockwise about shaft 44 so that feed pawl 111 advances disc 110 by one-twelfth of a rotation or through 30°. A stop-pin 131 on base plate 28 is positioned below free edge 121a of rocker arm 121, and the lower edge of free end 120a is normally positioned again stop-pin 131. Stop-pin 131 is effective to assure, by regulating the position of rocker arm 121, that feed pawl 111 is positively engaged in the next cut-out when rocker arm 121 is restored to its initial position after it has been advanced by actuation of solenoid Db with pawl 111 effecting an angular displacement of disc 110.

Check member 116 is mounted above disc 110 and has a base supported on a shaft connected to base plate 28, member 116 being spring-biased to move counterclockwise. A pin 116b attached to a free end 116a of check member 116 is normally engaged in one of the cut-outs of disc 110 for preventing reverse rotation of the disc. Free end 116a extends to a position in which it can engage and operate actuator Sw_{3a} of microswitch Sw₃ mounted above actuating bar Db₁ of solenoid Db. Free end 116a normally pivots clockwise about its supporting shaft against the spring bias as pin 116b is pushed out of a cut-out whenever disc 110 is moved by feed pawl 111, but end portion 116a does not close switch Sw₃.

As best seen in FIG. 23b, one protrusion 110a of the 12 formed in the outer periphery of disc 110 projects radially outwardly further than do the other 11 protrusions. Thus, free end 116a of check member 116 is pivoted through a larger angular distance whenever pin 116b moves over protrusion 110a, thereby closing switch Sw₃ to supply current to solenoid Da. Consequently, microswitch Sw₃ is closed once during each complete rotation of disc 110.

Referring again to FIGS. 19 and 20, a switch "closed time" holding member 132, formed of a thin resilient steel, is mounted below switch actuator Sw_{3a}. Member 132 is pivoted, at 132a, to base plate 28 through a rivet, and is spring-biased to swing clockwise. However, one arm 132b of member 132 engages a pin Db₂ secured to actuating bar Db₁ of solenoid Db so as to prevent such pivotal movement of member 132 in a clockwise direction. The other arm 132c of member 132 extends near actuator Sw_{3a}. Normally, member 132 is spring-

biased to pivot clockwise about pivot 132a as pin Db₂ moves, but the other arm 132c abuts against the end of actuator Sw_{3a} to prevent such movement of member 132. However, when pin 116a of check member 116 moves over the longer protrusion 110a of disc 110, and its free end 116a depresses actuator Sw_{3a}, the other arm 132c of member 132 moves beneath actuator Sw_{3a} and temporarily prevents return of the switch actuator to its original position so that switch Sw_{3a} is held closed.

If switch Sw₃ is closed, current is supplied to solenoid Da to actuate the same to operate the morning and afternoon switching mechanism. Holding member 132 is intended to maintain the current supply to solenoid Da while this switching mechanism operates. Member 132 is provided by taking into consideration the fact that, if the current supply to solenoid Da is shut-off before disc 108 has been moved through 60° by feed pawl 109, the morning and afternoon switching mechanism is not possible to be made operative. Discs 110, 112 and 114 are moved substantially instantaneously by the respective feed pawls 111, 113 and 115. However, since check members 116, 117 and 118 are spring-biased to press against the peripheries of the associated discs, the check members are brought substantially instantaneously into engagement with the next depression in the respective discs and consequently the contacts of microswitches Sw₃, Sw₄ and Sw₅, closed by free ends 116a, 117a and 118a of the respective check members, are opened in an instant. Thus, it is not possible to supply current to each solenoid during a time interval sufficiently long for it to cause the aforementioned clock switching mechanism to operate fully. Taking this fact into consideration, holding member 132 is specially provided so that it may operate to supply current to each solenoid for a time interval sufficiently long, when switching is effected from the minutes in units to the minutes-in-tens, from the minutes-in-tens to the hours in units, and from the hours in units to the morning or afternoon. Holding member 132, spring-biased clockwise, is moved counterclockwise by pin Db₂ on actuating bar Db₁ of solenoid Db as the actuating bar Db₁ is restored to its original position after operation. Thereby, holding member 132 is rendered inoperative to permit switch Sw₃ to open and interrupt current supply to the solenoid.

A minutes-in-tens transfer mechanism is disposed below the hours transfer mechanism, and is substantially similar to the latter except for the fact that disc 112, for rotating shaft 45 through one-twelfth of a rotation has two diametrically opposite protrusions 112a and 112b which have a greater radially outwardly extent than do the other 10 protrusions, as shown in FIG. 23c, that microswitch Sw₄ and check member 117 are disposed below disc 112, and that a "closed time" holding member 133 for the microswitch is shaped as shown in FIG. 22. Microswitch Sw₄ is mounted in the lower position due to space limitations, and pin 117b of check member 117 moves from below against the disc, with check member 117 being biased to move clockwise.

Holding member 133 is in the form of a bell crank, as shown in FIG. 22, and is spring-biased to pivot counterclockwise about pivot 133a of FIG. 19. However, such counterclockwise pivoting is limited by one arm 133b engaging the shaft pivotally mounting feed pawl 113. The other arm 133c of member 133 extends to near the

free end of actuator Sw_{4a} of switch Sw_4 , to engage this free end which is depressed as pin $117b$ rides over the longer protrusions $112a$ and $112b$ of disc 112 whereby switch Sw_4 can be temporarily held closed. Otherwise, this mechanism is identical with the hours transfer mechanism in that, when solenoid Dc is actuated, rocker arm 122 pushes pawl 113 to rotate disc 112 to in turn rotate shaft 45 through 15° . Further description is not believed necessary except to state that, since disc 112 makes one-half rotation in 60 minutes, it makes a complete rotation in 2 hours, and the microswitch Sw_4 is closed twice to activate solenoid Dc twice during this time period.

A minutes-in-units transfer mechanism is mounted below the minutes-in-tens transfer mechanism, and is similar to the latter in that solenoid Dd is activated to operate feed pawl 115 to intermittently rotate disc 114 . However, microswitch Sw_5 controlling current for solenoid Dc for the higher unit is mounted below disc 114 and its actuator Sw_{5a} is adapted to be engaged and operated by a free end $118a$ of check member 118 . This mechanism operates in a manner such that disc 114 makes one-tenth of a rotation, or a rotation of 36° , in 1 minute and, after the elapse of 10 minutes, when it has made one full rotation, the minutes-in-tens transfer mechanism is actuated. Thus, disc 114 has 10 cut-outs in its periphery and consequently 10 protrusions, with one protrusion $114a$ having a greater radial length than the other nine protrusions.

A "closed time" holding member 134 for microswitch Sw_5 , closed by this latter mechanism, is pivoted, at $134a$, through a shaft and in a position above switch Sw_5 (FIG. 19) and spring-biased counterclockwise. Member 134 has one arm $134b$, as best seen in FIG. 21, extending to near the free end of switch actuator Sw_{5a} and bent, at its forward end portion $134c$, toward base plate 28 . Bent portion $134c$ is arranged to engage a projection Sw_{5b} toward the free end of the switch actuator.

Member 134 has another arm $134d$ positioned against the end surface of a damper Ud mounted between the actuating bar of solenoid Dd and a fixed member, for inhibiting counterclockwise pivotal movement of member 134 . Respective dampers Ua , Ub and Uc are provided between the actuating bars of solenoids Da , Db and Dd and a fixed member to prevent the feed pawls from vibrating when they are suddenly pulled by the respective solenoids when the latter are energized.

The operation of the minutes transfer mechanism will be explained with reference to FIGS. 25, 26 and 27. A current is supplied to solenoid Dd when projection $95a$ of disc 95 of the clutch closes switch Sw_2 . If solenoid Dd is energized, actuating bar Dd_1 is retracted and rocker arm 123 pivots clockwise about shaft 46 so that feed pawl 115 advances disc 114 through an angle of 18° . At this time, damper Ud assures feed pawl 115 positively moving disc 114 . However, check member 118 , which is arranged to be pushed-out by the beveled portions of the cut-outs, executes pivotal movements through a small oscillating angle so that its free end $118a$ will not operate actuator Sw_{5a} of switch Sw_5 . Pin $118b$ of check member 118 is engaged in the next cut-out, as shown in FIG. 26, when feed pawl 115 has moved disc 114 through the predetermined angular

distance, thereby preventing reverse rotation of disc 114 .

On the other hand, damper Ud is compressed by actuating bar Dd_1 when retracted by solenoid Dd , so that holding member 134 tries to pivot counterclockwise about pivot $134a$. However, such pivotal movement is prevented by the bent forward end $134c$ abutting projection Sw_{5b} on actuator Sw_{5a} .

Thus, disc 114 makes one-tenth a rotation each time switch Sw_2 is closed, once each minute, by disc 95 rotated by motor SM at one RPM. When the disc has made one complete rotation after 10 minutes have elapsed, the longer protrusion $114a$ of disc 114 engages pin $118b$ of check member 118 and moves member 118 pivotally so that end $118a$ operates actuator Sw_{5a} of switch Sw_5 as shown in FIG. 27, and closes the switch. If actuator Sw_{5a} is operated, bent portion $134c$ of holding member 134 engages projection Sw_{5b} of the switch actuator, so that the switch is maintained in the closed position until the actuating bar of the solenoid is restored to its original position, even if check member 118 is engaged in the next cutout of disc 114 . If switch Sw_5 is closed, solenoid Dc of the higher unit is energized and renders the minutes-in-tens transfer mechanism operative.

As mentioned, disc 114 of the minutes transfer mechanism makes one-tenth of a rotation when driving shaft SMa of motor SM makes one rotation. When disc 114 has made one complete rotation after 10 minutes, the minutes-in-tens transfer mechanism is actuated. After 60 minutes has elapsed, the hours transfer mechanism is actuated and, after the elapse of twelve hours, the morning and afternoon switching mechanism is actuated.

The elapsed time is indicated by the figures and characters inscribed on time indicating rings 135 - 138 secured on the ends of shafts 43 - 46 , as shown in FIG. 40. More particularly, the outer peripheral surface of ring 135 on shaft 43 is divided into six equal arcuate length sections on which the characters "AM" and "PM" are inscribed in alternation. These characters can be viewed from outside through the window $11a$ shown in FIGS. 1, 2 and 7 and formed in cover $1b$.

The outer peripheral surface of indicating ring 136 on hours shaft 44 carries the figures "0" through "11" inscribed thereon at regular intervals, the peripheral surface of ring 137 on minutes-in-tens shaft 45 has the figures "0," "10," "20," "30," "40" and "50" inscribed thereon at regular intervals on each semi-cylindrical portion thereof, and the peripheral surface of ring 138 secured to minutes shaft 46 has the figures "0" through "9" inscribed thereon at regular intervals. These figures can be viewed through windows $11b$, $11c$ and $11d$, respectively, formed in cover $1b$, and indicate the hours, minutes-in-tens, and minutes-in-units as the shafts rotate. It should be understood that, in securing rings 136 - 138 to the respective shafts, the longer protrusions $114a$, $112a$, $112b$ and $110a$ of the discs must correspond, in position, to the last of the figures for indicating the time. It should also be understood that the cut-out discs shown in FIG. 23 and the cut-out discs for reciprocating the shield members, as shown in FIG. 24, must be made to correspond to each other in phase.

In the selected embodiment of the invention, as shown in FIG. 9, when shafts 43 through 46 rotate, the associated shield members reciprocate vertically starting from the one at the far right and proceeding toward the one at the far left, so as to shield and close the punch pin receiving openings of striker member 34 successively. Knobs 135a through 138a, having knurled surfaces, are provided on the outer surfaces of each of the respective indicating rings 135 through 138. By turning these knobs, it is possible to rotate the shafts manually to thereby adjust the time manually.

In the schematic wiring diagram of this embodiment of the invention, as shown in FIG. 31, electric potentials are supplied from an AC source and also from a DC source. Synchronous electric motor SM, adapted to rotate at 1 RPM, and solenoid plunger MG, for operating striking member 34, are connected to the alternating current power source, and solenoids Da through Dd, for operating respective shafts 43 through 46, for successively reciprocating the shield members in accordance with time, are arranged to be connected, during operation, to capacitors C1 and C2 normally charged by the DC current power source.

More particularly, motor SM and solenoid MG are connected in parallel, through a normally opened contact RL₁ of a relay, to the opposite terminals of the AC power source. Thus, if relay RL is energized and contact RL₁ is closed, solenoid MG is energized. Connected in series with the opposite terminals of capacitor C2, normally charged by the DC power source, are the normally open microswitch SW₀, adapted to be closed as front cover 1b is closed, the normally open switch SW₂, adapted to be closed by projection 96a of disc 96 rotated by motor SM, and solenoid Dd. Connected to the opposite terminals of a series circuit, consisting of switch SW₂ and solenoid Dd, are a series circuit consisting of the normally open microswitch SW₃ and solenoid Dc, a series circuit consisting of the normally open microswitch SW₄ and solenoid Dd, and a series circuit consisting of normally open microswitch SW₅ and solenoid Da. Blocking diodes d1 through d4 are connected in parallel with solenoids Da through Dd, respectively, to prevent electric current from flowing in the reverse direction when more than two of the microswitches are closed simultaneously with the passage of time.

Capacitor C1 is connected in parallel to the opposite terminals of capacitor C2 through a normally closed contact of switch SW which is actuated upon depression of "punch" button 13. A relay winding RL and normally closed microswitch SW₁ are connected in series to the opposite terminals of capacitor C2 through a normally open contact of switch SW. A normally open contact RL2 of relay RL is interposed between the relay winding and the normally open terminal of switch SW. Relay contacts RL2 and RL1 are arranged to be closed upon a flow of current from capacitor C1 to the relay winding through switch SW₁ when "punch" button 13 is depressed and switch SW is moved to the illustrated broken line position, so that alternating current can flow to solenoid MG. Switch SW₁ is effective to prevent relay RL from being energized, even if "punch" button is operated, when discs 95 and 96 rotate, and switch SW₂ is closed by projection 96a of disc 96 so as to actuate solenoid Dd for making all the transfer mechanisms

operative. Switch SW₁ is opened whenever switch SW₂ is closed.

The operation of the illustrated card punch, constructed as described, will now be explained. When a card is to be punched, by connecting motor SM to the source of AC potential, current is supplied to the motor, and the latter starts to rotate at one RPM. If cover 1b of casing 1 remains closed, the clutch mechanism remains disengaged so that the motor continues to rotate idly.

The operation of the card punch will be explained as used to punch holes in the card for recording information on the time required for performing an operation with a milling machine. Cover 1b is opened and knobs 135 through 138 of shafts 43 through 46, respectively, are turned so as to set the figures on the indicating rings 138 and 137 at zero, and the figures on the indicating ring 136 at zero, such figures being visible through the windows 11b through 11d. The character on indicating ring 139 may be set at either "AM" or "PM" depending on the occasion. In the example chosen for illustration, the character "PM" is indicated in window 11a. After this, operation knob 4 is turned to move belt 71 and set pointer 5 at the item "milling machine" on the work sheet. This causes card receiving members 57₁, 57₂ and 57₃ to pivot against the spring bias to open the card insertion passage across the higher three units, as shown in FIGS. 28 and 29. If front cover 1b is closed at this time, microswitch SW₀ is closed by fixture 15 and bell crank 83 is pivoted by fixture 16. This releases roller 89 of lever 85 from engagement with heart cam 98 of the clutch mechanism. At the same time, clutch operating lever 101 pivots outwardly so that ring 93 is moved axially of shaft 91 and ratchet teeth 92a of driving wheel 92 are engaged by pawls 102, 102 on driving shaft SMa, whereby the clutch mechanism is engaged. As the clutch mechanism is engaged, discs 95 and 96 begin to rotate and counting of the operation time is initiated. Each time 1 minute elapses, switch SW₂ is closed to actuate solenoid Dd to advance disc 114 through one-tenth of a rotation or 36°. As disc 114 is advanced, shield members 54, through 54₉ are successively moved into and out of the space between the rear end surfaces of punch pins M1 to M9 and the corresponding punch receiving openings M11 through M19. When disc 114 has made one complete revolution after the elapse of 10 minutes, the minutes-in-tens mechanism is actuated as described above, so that the 10 minutes that has elapsed is transferred to the disc 112 of the higher unit.

Let it be assumed that the operation is completed in 2 hours and 37 minutes. When the operation is completed, shield member 49₂, of all the shield members mounted on shaft 44, shield member 51₃, of all the shield members mounted on shaft 45, and shield member 53₇, of all the shield members mounted on shaft 46, are interposed between respective punch pins D₂, S₃ and M₇, and the associated receiving openings O₂₂, S₁₃ and M₁₇, with the indicating rings 135 through 138 indicating, respectively, "PM," "2," "30" and "7".

If a card 3, shown in FIGS. 5 and 6, is inserted through insertion slot 1c, the leading end of the card is received and stopped by the left and right end portions 57_{4d} and 57_{4e} of the upper edge of the fourth receiving member 57₄, as shown in FIGS. 28 and 29, so that the

card stops in this position. The card is formed beforehand with perforations by a sewing machine, as shown in FIG. 5, in positions in which holes are to be punched. The card is adapted to move into the card receiving passage through a distance corresponding to three rows of perforations when the first three uppermost receiving members are open. If "punch" button 13 is depressed after card 3 is inserted, switch Sw is transferred to the broken line position and the electric charge of capacitor C1 is discharged through relay RL to energize the relay and transfer the contacts RL1 and RL2 thereby to supply alternating current to solenoid MG. Upon such energization of solenoid MG, it pulls actuating lever MGa and causes striking member 34 to swing about shaft 36 to pivotal members 37 and 38. Responsive to such movement of striking member 34, punch pins M₁, S₃ and O₂ are pushed inwardly and their inner ends punch holes in card 3, as shown in FIG. 29. These holes are punched in card 3 in the position shown in FIG. 6. If a card punched as shown in FIG. 6 is applied to a read-out device, the symbols "PM," "2" and "37" are read, indicating that the milling machine operation has taken 2 hours and 37 minutes to perform.

From the foregoing description, it will be appreciated that the present invention permits punching holes in a card merely by inserting a card in the card punch and depressing the "punch" button, and that, in addition, it is possible to record, by punching holes in the card, the time required for the operation in units of hours and minutes and with ease.

In the above description, the invention has been described as recording the time required for the operation by punching holes in the card after setting the units of hours and minutes at zero. It should be understood that the time required for the operation can be recorded by adjusting the operation knob and depressing the "punch" button when the operation is initiated and again after the operation is completed, if the timing device is set according to clock time. Unlike known time cards, the card processed in accordance with the invention records time by punched holes, in place of having symbols inscribed thereon. Thus, the invention provides a card punch device having a high practical value.

While switches Sw₁ and Sw₂ have been described as formed separately to be opened and closed, respectively, by projections 95a and 96a of discs 95 and 96, respectively, it should be understood that, since switch Sw₁ is a normally closed switch and switch Sw₂ is a normally open switch, they can be combined into a single unit which can be operated by a single projection on a single disc. It should also be understood that the cut-out discs, used for reciprocating the shield members, can be replaced by discs with projections or by cam plates, without requiring the exercise of further inventive ingenuity.

While a specific embodiment of the invention has been shown and described in detail to illustrate the application of the principles of the invention, it will be understood that the invention may be embodied otherwise without departing from such principles.

What is claimed is:

1. A card punch comprising, in combination, means forming a card insertion slot communicating with a card receiving passage; receiving members mounted

for movement into and out of said passage; an operation device controlling movement of said receiving members into and out of said passage to control the depth of insertion of a card through said slot into said passage; a plurality of punch pins mounted for reciprocation across said passage to punch holes in a card therein; a striking member movable towards said passage and formed with a number of holes equal to the number of punch pins and each aligned with a respective punch pin having a first end adjacent a card in said passage and a second end adjacent but spaced from said striking member and enterable into a respective associated hole in said striking member, unless blocked, upon such movement of said striking member; a plurality of shield members equal in number to the number of punch pins and each selectively interposable, in an operative position, between the second end of a respective punch pin and the associated opening in said striking member to block the respective punch pin entering the associated opening upon striking movement of said striking member; respective cam means effecting movement of said shield members to such operative positions; a timing device operating said cam means to move said shield members to the operative positions only at respective indicated times whereby, at any selected instant, only those shield members corresponding to the indicated time are in the operative positions; and means selectively actuatable at any selected instant to move said striking member to cause only those punch pins then having the associated shield member in the operative position to move across said passage to punch holes in a card in the passage.

2. A card punch, as claimed in claim 1, including an indicator, visible from the exterior of said card punch, and positioned by said operation device to indicate the depth of card insertion selected by said operation device.

3. A card punch, as claimed in claim 1, in which said punch pins are arranged in three sets, one set of punch pins punching holes indicating the hours, the second set punching holes indicating the minutes-in-tens and the third set of punch pins punching holes indicating the minutes-in-units.

4. A card punch, as claimed in claim 3, in which said punch pins punch further holes indicating whether the time is "AM" or "PM."

5. A card punch, as claimed in claim 1, in which said punch pins are arranged in first, second and third rows, said first row including eleven punch pins indicating the time in hours, said second row including five punch pins indicating the minutes-in-tens, and said third row including nine punch pins indicating the minutes-in-units; said shield members being arranged in three sets, with each set being operatively associated with a respective row of punch pins; said cam means including first, second and third cam means each controlling movement of the shield members of a respective set; each cam means moving its controlled shield members successively to the operative position, and retracting its controlled shield members, from one end of the associated row of punch pins to the other.

6. A card punch, as claimed in claim 5, including first, second and third rotatable shafts each having one set of cam means secured to rotate therewith; said first, second and third shafts being correlated with said first,

second and third rows of pins through the cam-controlled shield members; first, second and third stepping cams secured to said first, second and third shafts, respectively; first, second and third stepping means each associated with said first, second and third stepping cams, respectively; said third shaft performing one complete rotation in 10 steps, said second shaft performing one complete rotation in six steps, and said first shaft performing one complete rotation in 12 steps; a synchronous motor operable at 1 RPM; means connecting said synchronous motor to said third stepping means and operable, responsive to each rotation of said synchronous motor, to effect rotation of said third stepping cam through one step; means connecting said third stepping cam to said second stepping device and operable, responsive to one complete rotation of said third stepping cam, to effect rotation of said second stepping cam through one step; and means connecting said second stepping cam to said first stepping device and operable, responsive to one complete rotation of said second stepping cam to rotate said first stepping cam through one step.

7. A card punch, as claimed in claim 5, in which each of the shield member controlling cams on a respective shaft comprises a peripheral portion engageable with an abutment on the associated shield member to move the latter to the operative position; the peripheral portions of axially successive controlling cams being staggered angularly with respect to each other.

8. A card punch, as claimed in claim 1, including a casing in which the components of said punch are mounted; a front door controlling access to the interior of said casing; and a normally opened switch in said casing controlling connection of said punch through a source of electric potential and closed only responsive to closing of said front door.

9. A card punch, as claimed in claim 1, in which said last named means comprises a solenoid connected to said striking member to move the latter toward said passage; and a "punch" button controlled switch controlling energization of said solenoid.

10. A card punch comprising, in combination, means forming a card insertion slot communicating with a card receiving passage; receiving members mounted for movement into and out of said passage; an operation device controlling movement of said receiving members into and out of said passage to control the depth of insertion of a card through said slot into said passage; a plurality of punch pins mounted for reciprocation across said passage to punch holes in a card therein; a striking member movable towards said passage and formed with a number of holes each aligned with a respective punch pin; each punch pin having a first end adjacent a card in said passage and a second end adjacent but spaced from said striking member; a plurality of shield members each selectively interposable, in an operative position, between the second end of a respective punch pin and the associated opening in said striking member; cam means controlling movement of said shield members to such operative positions; a timing device operating said cam means to move said shield members to the operative

positions only at respective indicated times whereby, at any selected instant, only those shield members corresponding to the indicated time are in the operative positions; means selectively actuatable at any selected instant to move said striking member to cause only those punch pins then having the associated shield member in the operative position to move across said passage to punch holes in a card in the passage; said punch pins being arranged in first, second and third rows, said first row including 11 punch pins indicating the time in hours, said second row including five punch pins indicating the minutes-in-tens, and said third row including nine punch pins indicating the minutes-in-units; said shield members being arranged in three sets, with each set being operatively associated with a respective row of punch pins; said cam means including first, second and third cam means each controlling movement of the shield members of a respective set; each cam means moving its controlled shield members successively to the operative position, and retracting its controlled shield members, from one end of the associated row of punch pins to the other; first, second and third rotatable shafts each having one set of cam means secured to rotate therewith; said first, second and third shafts being correlated with said first, second and third rows of pins through the cam-controlled shield members; first, second and third stepping cams secured to said first, second and third shafts, respectively; first, second and third stepping means each associated with said first, second and third stepping cams, respectively; said third shaft performing one complete rotation in 10 steps, said second shaft performing one complete rotation in six steps, and said first shaft performing one complete rotation in 12 steps; a synchronous motor operable at 1 RPM; means connecting said synchronous motor to said third stepping means and operable, responsive to each rotation of said synchronous motor, to effect rotation of said third stepping cam through one step; means connecting said third stepping cam to said second stepping device and operable, responsive to one complete rotation of said third stepping cam, to effect rotation of said second stepping cam through one step; means connecting said second stepping cam to said first stepping device and operable, responsive to one complete rotation of said second stepping cam to rotate said first stepping cam through one step; each stepping means including a respective pawl, engageable with the respective stepping cam and a respective solenoid which, when energized, actuates the associated pawl to step the associated stepping cam through one step; said means connecting said stepping cams to said stepping devices comprising switches operated by the stepping device for each stepping cam when the associated stepping cam has completed a full rotation; and respective switch-holding means operable by each stepping device, when actuating the associated switch controlled thereby, to retain the associated switch energized until the solenoid controlled thereby has completed its full stroke; the controlled solenoid, upon full actuation, releasing the associated switch-holding means.
